CLAIM

The ornamental design for a USB storage device, as shown and described.

DESCRIPTION

FIG. 1 is a top perspective view of a USB storage device showing my new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view thereof in an alternate configuration of use; and,

FIG. 10 is another perspective view thereof with alternate broken line environment.

The dash-dash broken lines in the drawings depict the portions of the USB storage device that form no part of the claimed design.

1 Claim, 10 Drawing Sheets
